Design Patent Application for Filter Cap, Design U.S. Appl. No. 29/590,423, filed Jan. 10, 2017, Applicant Scientific Plastic Products, Inc.

Primary Examiner — John A Voytek

(74) *Attorney, Agent, or Firm* — Stetina Brunda Garred and Brucker

(57) **CLAIM**

The ornamental design for a filter cap, as shown and described.

DESCRIPTION

FIG. 1 is a top perspective view of a filter cap showing our new design;

FIG. 2 is a bottom perspective view of the filter cap of FIG. 1;

FIG. 3 is a top plan view of the filter cap of FIG. 1;

FIG. 4 is a side view of the filter cap of FIG. 1 with the opposing back view being a mirror image thereof;

FIG. 5 is a left side view of the filter cap of FIG. 1, with the opposing right side view being a mirror image thereof; and,

FIG. 6 is a bottom plan view of the filter cap of FIG. 1. The broken lines in FIGS. 1-6 of the drawings are for the purpose of illustrating portions of the filter cap, which form no part of the claimed design.

1 Claim, 5 Drawing Sheets
